DESIGN FOR A HOSIERY BAND OR THE LIKE

Victor Lebow, New York, N. Y., assignor to Chester H. Roth Co., Inc., New York, N. Y.

Application December 19, 1942, Serial No. 109,067

Term of patent 14 years

To all whom it may concern:

Be it known that I, Victor Lebow, a citizen of the United States, residing at New York, county of New York, and State of New York, have invented a new, original, and ornamental Design for a Hosiery Band or the like, of which the following is a specification, reference being had to the accompanying drawing, forming a part thereof.

band, embodying my new design, before folding.

Figure 2 is a side elevational view thereof as it appears when in use, with the hosiery shown in dotted lines, and

I claim:

The ornamental design for a hosiery band or the like, as shown.

VICTOR LEBOW.
